UNITED STATES PATENT OFFICE.

HENRY K. MYERS, OF SWISSVALE, PENNSYLVANIA.

RAIL-TIE.

No. 850,951.

Specification of Letters Patent.

Patented April 23, 1907.

Application filed February 13, 1907. Serial No. 357,114.

To all whom it may concern:

Be it known that I, HENRY K. MYERS, a citizen of the United States, residing at Swissvale, in the county of Allegheny and State of Pennsylvania, have invented a new and useful Improvement in Rail-Ties, of which improvement the following is a specification.

My invention has for its object the provision of a tie which can be produced with a minimum amount of material at a minimum cost, give a maximum support to the rails, distribute the train-load evenly over the road-bed, be simple in construction, have maximum life, &c., which objects I attain in the construction and arrangement of parts, as will be hereinafter described in detail and later pointed out in the appended claims.

In the accompanying drawings several views are shown, in which—

Figure I is a plan of a short section. Fig. II is a transverse section. Fig. III is a longitudinal section. Fig. IV is a plan of the spreader-blank. Fig. V is a perspective of one of the keys. Fig. VI is a perspective of a portion of the rail-clamping members; and Fig. VII is a perspective of a portion of a modified form of rail-clamp member.

Similar letters of reference denote like parts throughout the following description.

The structure shown comprises a pair of parallel-disposed metal members or ties A, which in cross-section resemble that of an inverted T, thus giving a broad and substantial surface-contact at the bottom of the road-bed. A pair of spreader-plates B, extending beneath and paralleling the rails, are employed to form a tie extension or support proper for the rails and connect the two tie members together. These plates are each formed of comparatively broad and moderately heavy sheet metal, (see blank at Fig. II,) the body portion proper having oppositely and downwardly disposed tongues C formed thereon to assist in preventing lateral displacement, the extremities of the plate being bent transversely to form vertically-disposed arches or supports D of greater height than and engaging over the web of the ties, to which they are firmly secured by rivets E, said arch portions having a tapered opening F formed transversely at the top. The rails are maintained in operative position upon the supporting-arch portions of the spreader-plates by a pair of clamp-plates G,

which are of sufficient length to extend across both arches, said clamp-plates being of such form, when placed together, as to embrace the base or flange of the rail, each of which is provided with a downwardly-extended flange G', which engages in and is correspondingly tapered to the said opening F in the supporting-arch. These clamp-plates are further provided with openings H, which register with the space in the arches above the connection with the ties and are securely held in position by split keys I, driven through the openings in the clamp-plates, the small ends of which are spread apart after being driven to prevent displacement.

The form of clamp-plates G with extension to embrace the rail-web as well as the base may be employed throughout the structure, and when employed at the rail-joints openings J are formed therein to register with those of the rail ends, and thus perform the double function of rail-clamps and fish-plates; but, if desired, the form G may be dispensed with where no joints occur, or for that matter they may be dispensed with at all points and the form G'' made use of, the old form of fish-plate being employed in connection therewith at the rail-joints.

A thin piece of cardboard, asbestos, or other suitable material (not shown) is to be employed between the base of the rails and the clamps for the purpose of cushioning and deadening sound.

The structure is buried in the road-bed to a point on a level with the base of the rails, practically leaving nothing visible above ground but the rails, said structure being admirably adapted to carry out the objects set forth.

While I have shown and described minutely a certain form of structure, I do not wish it to be understood that I limit myself thereto, as said structure may be varied without departing from the scope of my invention.

Having thus fully shown and described a practical and operative means to carry out my invention, what I claim is—

1. The combination of a pair of cross-ties connected together by a pair of spreaders extending on a plane below and paralleling the rails, said ties having upwardly-extended rail-supporting portions on a plane above the tie-body proper, and members carried by said supporting portions to secure the rails thereto.

2. The combination of a pair of cross-ties connected together by a pair of spreaders extending on a plane below and paralleling the rails, said ties having upwardly-extended rail-supporting portions on a plane above the tie-body proper, members carried by said supporting portions to clamp the rails, and means engaging said clamps and supporting portions to maintain the same in position.
- 10 3. The combination of a pair of cross-ties, a pair of spreader-plates connecting said ties on a plane below and paralleling the rails the ends thereof being disposed upwardly to form supports for the rails, rail-clamping plates carried by said supports, and members securing said plates to said supports.
- 15 4. The combination of a pair of cross-ties, a pair of spreader-plates connecting said ties below and paralleling the rails the ends thereof over the ties proper being disposed upwardly to form supports for the rails, rail-clamping plates carried by said supports, and members securing said plates to said supports.
- 20 5. The combination of a pair of cross-ties, a pair of spreader-plates connecting said ties
- below and paralleling the rails the ends thereof over the ties proper being disposed upwardly to form supports for the rails and provided with a downwardly-disposed slot, rail-clamping plates having downwardly-disposed portions engaging in said slots, and members securing said plates to said supports.
- 30 6. The combination of a pair of cross-ties, a pair of spreader-plates connecting said ties below and paralleling the rails, the ends thereof over the ties proper being disposed upwardly to form supports for the rails and provided with a downwardly-disposed slot, rail-clamping plates having downwardly-disposed portions engaging in said slots, and members securing said plates to said supports, said spreader-plates being further provided with projections on their under sides to prevent displacement.
- 35 40 45

In testimony whereof I have hereunto signed my name in the presence of two subscribing witnesses.

HENRY K. MYERS.
